CLAIM

The ornamental design for a skort as shown and described.

DESCRIPTION

FIG. 1 is a front elevation view of a skort in a first position; FIG. 2 is a rear elevation view of the skort of FIG. 1; FIG. 3 is a right side view of the skort of FIG. 1; FIG. 4 is a left side view of the skort of FIG. 1; FIG. 5 is a top plan view of the skort of FIG. 1; FIG. 6 is a bottom plan view of the skort of FIG. 1; FIG. 7 is a front elevation view of the skort of FIG. 1 in a second position; FIG. 8 is a rear elevation view of the skort of FIG. 7; FIG. 9 is a right side view of the skort of FIG. 7; and, FIG. 10 is a left side view of the skort of FIG. 7. The evenly broken lines (dash-dash lines) shown in the Figures are only for illustrative purposes to show visible environmental structure and form no part of the claimed invention.

1 Claim, 10 Drawing Sheets
